(57) **CLAIM**

The ornamental design for a pipette, as shown and described.

DESCRIPTION

FIG. 1 is a top, front, right side perspective view of a pipette, showing our new design;

FIG. 2 is a bottom, rear, right side perspective view thereof;

FIG. 3 is a front view thereof,

FIG. 4 is a rear view thereof,

FIG. 5 is a left side view thereof,

FIG. 6 is a right side view thereof;

FIG. 7 is an enlarged top view thereof;

FIG. 8 is an enlarged bottom view thereof;

FIG. 9 is an enlarged view of a portion labelled 9 in FIG. 1; and,

FIG. 10 is an enlarged view of a portion labelled 10 in FIG. 2.

The dash-dash broken lines in the drawings depict portions of the pipette that form no part of the claimed design.

The dash-dot-dash broken lines depict the bounds of the enlarged views that form no part of the claimed design.

1 Claim, 10 Drawing Sheets
